FLASHLIGHT HOLDER

Edward A. Bernstein, Cedarhurst, N. Y.

Application September 4, 1942, Serial No. 457,269

4 Claims. (Cl. 67—31)

1

My invention relates to a new and improved flashlight holder.

The improved device is particularly adapted for use with flashlight bulbs which are used for taking flashlight photographs. After a bulb of this type has been used, it is hot so that it is difficult to use such devices, if it is desired to take a series of photographs in quick succession. According to my invention, the used bulb can be conveniently ejected from the holder, and without handling said used bulb.

Another object of my invention is to provide a device which may be applied as an attachment to existing devices.

Another object of my invention is to provide a device which will use a minimum of metal parts.

Other objects of the invention will be stated in the annexed description and drawings which illustrate a preferred embodiment thereof.

Fig. 1 is a sectional view on the line 1—1 of Fig. 3, showing a portion of the flashlight bulb.

Fig. 2 is a vertical elevation, taken at the right-hand side of Fig. 1.

Fig. 3 is a top plan view of the device, the representation of the bulb being omitted.

Fig. 4 is an elevation, partially in section, showing the principal element of the improved device.

Fig. 5 is a sectional view on the line 5—5 of Fig. 2, showing the latch member in its release position, as distinguished from the operative position of said latch member which is shown in Figs. 1—3 inclusive.

The invention is shown in the form of an attachment which may be applied to any conventional flashlight casing. Many of the details of the conventional flashlight casing are therefore not shown, as they are well-known per se. The flashlight casing 1 has a wall of insulating material and it is provided with the usual switch 2, which has the usual finger-operated button 2a, which is moved to open or to close the circuit of the bulb.

The socket in which the flashlight bulb B is received consists of a base or inner part 5, which is integral with an outer cup member 3. This socket 3—5 is made of any suitable insulating material. In this particular embodiment, the base 5 has its outer longitudinal wall shaped to provide a helical thread which has a longitudinal axis, in order to adapt the attachment to a flashlight casing which has a helically threaded metal shell 26. However, the outer longitudinal wall of the base 5 may be of smooth cylindrical shape, instead of having a helical thread. A metal strip 6, which is designated as a contact strip or circuit

2

strip, is located within the cup member 3. Said cup member 3 is of greater external diameter than the base 5, thus forming a shoulder 5a. The metal contact strip 6 is integral with a metal extension 4 which extends through a narrow bore in the shoulder 5a. The extension 4 abuts the outer wall of the base 5. The strip 6 and its extension 4 constitute a single metal strip which has an outer end-part above shoulder 5a and which is located laterally inwardly of the socket 3—5, and said single metal strip has an inner end-part below shoulder 5a which is external to said socket 3—5. The shell 26 is designated as a casing-contact-member, which contacts with said inner end-part. The strip 6 and the extension 4 are preferably of uniform width. The contact metal strip 6 is held in position by means of a force fit in the bore of the shoulder 5a, or in any suitable manner. A housing 11, which can be made of metal or of any other material, conducting or non-conducting, is fixed to the cup member 3, so that said housing 11 extends laterally from said cup member 3. A compression spring 21 is located in the housing 11. The lateral outer end of the compression spring 21 abuts the inner face of the lateral outer wall of the lateral housing 11. The inner lateral end of the compression spring 21 abuts the head 20a of a latch 16, which can move laterally back and forth in a suitable opening which is provided in the wall of the cup member 3. The compression spring 21 normally holds the latch member 16 in the holding position which is shown in Fig. 1. A lever 9, which can be made of insulating material or of any other material, is turnably connected to the wall of the cup member 3, by means of the pivot pin 10. The shank 20 of the head 20a extends through a bore of the lever 9. Said shank 20 has an outer head 12. This head 12 can be fixed to the outer end of the shank 20, after said shank has been passed through the bore of the lever 9. When the lever 9 is turned to the position shown in Fig. 5, the latch member 16 is moved to the release or inoperative position which is shown in Fig. 5. A metal conducting wall-pin 25a is fixed to the lateral end wall of the base 5. One end of the compression spring 7 is fixed to said contact pin 25a in any suitable manner. A metal shell 26 is fixed to the inner wall of the casing 1 in the conventional manner. In this embodiment, said metal shell 26 is corrugated, in order to provide the conventional helical thread. Hence, in this embodiment the base 5 can be screwed into the metal shell 26. The metal extension strip 4 will then make good electrical

contact with the metal shell 26. Fig. 1 diagrammatically shows one of the dry cells E which is used in flashlight devices. I have not illustrated the details whereby the circuit of the filament of the bulb B can be closed or opened by moving the button 2a of the switch 2, as such details are well-known per se.

The bulb B is provided with the usual metal shell S. This shell or sleeve S has a longitudinal axis which is coincident with the longitudinal axis of the socket 3—5, when the bulb B is assembled with said socket. When the bulb B is inserted into the cup member 3, as shown in Fig. 1, a part of the outer longitudinal wall of said metal shell S abuts the metal contact strip 6, 10 in order to make good electrical contact. The bulb B is also provided with the conventional metal central contact 25, which is insulated from the shell S. One end of the filament of the bulb B is connected to the shell S, and the other end of said filament is connected to the central contact 25. These conventional details are not illustrated in the drawings. In addition to providing good electrical contact, the strip 4 serves frictionally to retain the base 5 in the flashlight casing, if the shell 26 is of the smooth or uncorrugated type.

The latch member 16 is located between adjacent lateral corrugations of the shell S, when said latch member 16 is in its operative position. The longitudinal ejector spring 7 is then under longitudinal compression. If the lever 9 is then turned to the inoperative or release position shown in Fig. 5, the latch member 16 will be moved to its inoperative or release position against the force of the compression spring 21, which normally maintains the latch member 16 in its operative or holding position. When the latch member 16 is located in said inoperative position, the longitudinal compression spring 7 can eject the bulb B longitudinally from the device with suitable gentle force by sliding said longitudinal shell S and the longitudinal shank of bulb B out of the socket 3—5, so that the bulb B can be ejected into a waste basket or other suitable receptacle, without breaking said bulb. The spring 7 electrically connects the metal contact pin 25 of bulb B to the metal pin 25a of the lateral end-wall of base 5. Said spring 7 is insulated from the metal shell S. The bulb has insulating material of the conventional type, which extends below the metal shell S, and through which the pin 25 projects. The outer end of the spring 7 abuts this insulating material, so that the spring 7 does not contact with the metal shell S. As shown in Fig. 1, the outer end-part of the metal strip 6—4 is smooth, and its inner end-part is shaped to interfit with the thread of shell 26, so that the base 5 can be screwed into the casing 1.

The metal shell 26 is connected to one of the terminals of the switch 2 in the usual manner, and the other terminal of said switch 2 is connected in the usual manner to the bottom contact of the battery or batteries E.

By utilizing a relatively narrow strip of metal 6, I provide the necessary electrical connections between the conventional flashlight casing and the improved device, with a minimum use of metal.

When the socket 3—5 is inserted as an attachment into the flashlight casing 1, the shoulder 5a abuts the top or outer edge of said flashlight casing 1.

For convenience, the parts of the device are 75

described in the claims with reference to their relative vertical positions which are shown in Fig. 1, although the device can be used in any position.

5 I have described a preferred embodiment of my invention, but it is clear that numerous changes and omissions can be made without departing from its spirit.

I claim:

1. An ejector socket for a flash-bulb of the type which has an external longitudinal metal sleeve and a contact pin which is located at the inner end of said metal sleeve and which is insulated from said metal sleeve, said socket having a longitudinal wall and a lateral inner end-wall, said socket having an inlet opening at one end thereof, said walls of said socket being made of insulating material, a longitudinal metal contact strip which has an outer end-part which is located laterally inwardly of said socket adjacent said inlet opening, said contact strip extending through a bore of said longitudinal wall and having an inner end-part which is located laterally outwardly of said longitudinal wall adjacent said inner end-wall, said outer end-part of said contact strip being smooth to permit free longitudinal movement of said metal sleeve relative to said socket, said inner end-wall having a metal wall-pin fixed thereto, a longitudinal ejector spring which extends longitudinally from said inner end-wall towards said inlet opening, said ejector spring being located in said socket, the inner end of said ejector spring being fixed to said wall-pin, and latch means associated with 20 said socket for releasably retaining a bulb therein against the force of said ejector spring.

2. A holder for a flash bulb, said flash bulb being of the type which has an external metal sleeve which has a contact pin which is located 30 at the inner end of said metal sleeve, said contact pin being insulated from said metal sleeve, said metal sleeve having a longitudinal axis, said holder comprising a longitudinal socket which is made of insulating material, said socket having an inlet opening at its outer end and a lateral inner end-wall which is made of insulating material, a longitudinal metal wall-pin which is fixed to and which extends through said lateral inner end-wall, said socket being constructed and 40 shaped loosely and longitudinally to receive said metal sleeve so that said metal sleeve can be ejected from said socket by sliding said metal sleeve longitudinally out of said socket, a metal ejector spring, one end of said ejector spring 45 being fixed to said wall-pin, the other end of said ejector spring being located to abut said contact pin of said bulb, a longitudinal metal strip which has an outer end-part and an inner end-part, said outer end-part being located laterally inwardly of the inner longitudinal wall of said socket, said outer end-part being located to contact with said metal sleeve of said bulb longitudinally inwardly of said inlet opening, said inner end-part extending through the 50 wall of said socket and being laterally external to said socket, a casing in which said socket is mounted, said casing being made of insulating material, said casing having a casing contact-member which contacts with said inner end-part, 55 said casing having a casing-switch, one terminal of said casing-switch being connected to said casing contact-member and hand-operated latch-means for releasably retaining said bulb in said socket against the action of said ejector spring.

60 70 3. A holder according to claim 2, in which

said casing contact-member is sleeve-shaped and provided with a thread which has a longitudinal axis, said inner end-part has a corresponding thread, said socket has a lateral external shoulder between said inlet opening and said lateral inner end-wall, said shoulder having a bore through which said metal strip extends, said shoulder abutting an end-wall of said casing.

4. A holder according to claim 2, in which said latch-means are located externally to said socket and said casing.
